(57) **CLAIM**

The ornamental design of a fly repeller fan, as shown.

DESCRIPTION

FIG. 1 is a top perspective view of the fly repeller fan showing my new design;

FIG. 2 is a bottom perspective view of the fly repeller fan;

FIG. 3 is a top plan view of the fly repeller fan;

FIG. 4 is a bottom plan view of the fly repeller fan;

FIG. 5 is a front elevational view of the fly repeller fan;

FIG. 6 is a rear elevational view of the fly repeller fan;

FIG. 7 is a right side elevational view of the fly repeller fan;

FIG. 8 is a left side elevational view of the fly repeller fan;

FIG. 9 is an enlarged view of portion 9 shown in FIG. 1; and,

FIG. 10 is an enlarged view of portion 10 shown in FIG. 1. The broken lines in the drawings depict portions of the fly repeller fan that form no part of the claimed design.
